R. P. HOLYSZ

SKYLIGHT

Filed March 28, 1923

UNITED STATES PATENT OFFICE.

ROMAN P. HOLYSZ, OF CHICAGO, ILLINOIS.

SKYLIGHT.

Application filed March 28, 1923. Serial No. 628,198.

My invention relates to skylights.

One of the objects of my invention is the provision of a skylight of simple, strong, durable and inexpensive construction so arranged that its parts may be fabricated in the factory, conveniently nested if desired so as to occupy a minimum amount of space when in storage or when crated, shipped or carted to the place of installation, and readily assembled and erected without the necessity of soldering any of the joints or the use of any but a few of the most common tools, such, for example, as a hammer, a wrench, a pair of pliers or a screw driver.

A further object of my invention is the provision of a skylight having a curb portion so constructed that it may be placed over the skylight opening in a roof and quickly attached to the roof with a few nails or screws without the necessity of building a curb on the roof of the particular size to receive the curb of a particular skylight, thus making it unnecessary for any close co-operation between the builder of the skylight and the carpenter making the skylight opening in the roof.

A further object of the invention is the provision of a skylight having a curb portion, a cover portion which is supported in spaced relation to the curb portion, and swinging means for closing the openings in the respective sides between the curb and cover portions in combination with novel means for opening and closing the closure means.

The invention consists in the novel constructions and arrangements to be hereinafter described and claimed for carrying out the above stated objects and such other objects as will appear from the following description of a certain preferred embodiment illustrated in the accompanying drawings, wherein—

Fig. 1 is a perspective view of a skylight embodying the principles of my invention;

Fig. 2 is a sectional view, on an enlarged scale, taken on the line 2—2 of Fig. 1; and

Fig. 3 is a sectional view, on an enlarged scale, taken on the line 3—3 of Fig. 2.

Like characters of reference designate like parts in the several views.

The skylight shown in the accompanying drawings is adapted to be erected on a relatively flat roof, but I do not intend to limit my invention to a skylight for use only in

connection with such roofs, as it will be obvious from the following specification that a skylight embodying at least certain principles of my invention may be readily constructed and applied to other types of roof.

The skylight is preferably formed of metal and comprises a curb portion, a cover portion, means for supporting the cover portion in spaced relation with respect to the curb portion, and means for closing the spaces in the respective sides between the curb and cover portions. The sides 5 of the curb portion slant outwardly and are surrounded at the base by an outwardly extending flange 6. The upper edges of the curb sides are bent inwardly substantially at right angles to provide a sill portion 7 and are then bent upwardly to provide a stiffening portion 8. The frame of the cover portion may be of any desired construction but preferably includes a base frame 9 bent so as to provide a stiffening portion 10 and a depending vertical flange 11. The cover portion is separable from and is supported in spaced relation with respect to the curb portion by means of detachable angle posts or legs 12 which are placed at the corners, being fastened at their upper ends to the inner sides of the flanges 11 by bolts or rivets 13 and at their lower ends to the outer sides of the curb sides 5 by means of bolts 14. The spaces in the respective sides of the skylight between the legs 12 and the curb and cover portions are preferably closed by closure means 15 which are preferably separable from the cover and curb portions. The closure means may be attached to the skylight structure in any preferred manner, for example, by hinges 16 carried by the respective sides of the frame 9 of the cover portion.

The means preferably employed for operating the several closure members 15 will now be described. An L-shaped arm 17 is provided for each of the closure members, one leg of the arm being rigidly attached to the inner side of the closure member, while the other leg of the arm carries an adjustable counter-weight 18. The counter-weights are adjusted on the respective arms so that normally they will hold the respective closure members in open position, the respective counter-weights being secured in such position by set screws 19. The members 15 are preferably closed simultaneously and to ac-

complish this result the respective weights 18 are connected by members 20 to a common flexible member 21 which operates over a sheave 22 supported by a bracket 23 fastened 5 to the under side of the cover portion. The sheave 22 is provided with a main circumferentially extending groove 24 and a plurality of obliquely disposed grooves 24^a leading therefrom to either side thereof. It will be apparent, therefore, when the free end of the member 21 is held straight, that it will run freely in the groove 24 and thus the free ends of the arms 17 and the respective counter-weights 18 carried thereby may be 15 raised or lowered. When the closure members 15 are in the desired position, the free end of the member 21 may be held against movement over the sheave 22 by pulling it over to one side or the other so it will be 20 caught in one of the grooves 24^a.

A plurality of parallelly arranged plates 25 is supported in a frame 26 adapted to rest upon ledges 27 provided on the inner side and adjacent the base of the curb portion.

The roof of the building is provided with the usual skylight opening 28, the portions of the roofing boards 29 adjacent the opening being supported by joists 30. It will be noted that the base flange 6 surrounding the 35 curb portion is made relatively wide and that it is adapted to rest upon the portions of the roofing boards 29 which are adjacent the opening 28 in the roof, the skylight being secured to the roof by driving nails through the flanges 6 into the roofing boards. It is 40 unnecessary, therefore, for a curb to be built on the roof to receive the skylight as is the common practice. The skylight may be readily installed over an opening in the roof 45 which is somewhat larger or somewhat smaller than the internal dimensions of the skylight curb. The skylight may be installed on the roof before the roofing paper 31 is applied, which is advantageous because it avoids the possibility of injury to the roofing paper by workmen installing the skylight. The joint between the roofing paper and the skylight is made watertight by any 50 suitable cementitious substance 32 being placed over the flange 6 of the skylight curb

and under the adjacent portions of the roofing paper. It is unnecessary, therefore, to employ a flashing around the skylight.

It will be noted that all the parts of the skylight may be fabricated at the factory. 55 Since the curb portion has sloping sides, a number of them may be readily nested. The legs 12 and the closure members 15 may be attached to the cover portion of the skylight at the factory but they are preferably attached at the place of installation. When the cover portions are of pyramidal form as shown in the drawing a number of them may be nested. The parts, therefore, occupy a minimum amount of space when in storage or when crated for shipment. No special tools are required in erecting the skylight and no soldering of joints is necessary.

The plates 25 are arranged so that the rays of light entering through the glazed cover portion of the skylight will strike against them and be deflected or diffused. A skylight embodying this feature of my invention has every advantage of the saw-tooth type of skylight in common use, which is relatively expensive to construct and admits only a relatively small quantity of light.

I do not intend to limit my invention to the details of construction shown and described, except only in so far as certain of the appended claims are specifically so limited, as it will be obvious that modifications may be made without departing from the principles of the invention.

I claim:

In a skylight, the combination of a curb portion, a cover portion, legs connected at their lower ends to said curb portion and at their upper ends to said cover portion for supporting said cover portion in spaced relation with respect to said curb portion, closure means hingedly connected to said cover portion for closing the respective openings between said legs and said cover and curb portions, arms attached to said respective closure means, counter-weights carried by said respective arms, and means to move said arms.

ROMAN P. HOLYSZ.
